UNITED STATES PATENT OFFICE.

MYER DITTEHOFER, OF NEW YORK, N. Y.

DESIGN FOR A CASE FOR THERMOMETERS, &c.

SPECIFICATION forming part of Design No. 13,695, dated March 6, 1883.

Application filed December 5, 1882. Term of patent 3½ years.

To all whom it may concern:

Be it known that I, MYER DITTEHOFER, a citizen of the United States, residing at the city of New York, in the county and State of New York, have invented and produced a new and original Design for Cases for Thermometers, Pulsometers, and other Articles, of which the following is a specification.

The nature of my design is fully represented in the accompanying drawings, in which—

Figure 1 is a side elevation of my newly-designed case; and Fig. 2, a transverse section of the same, taken on the line 2 2 of Fig. 1.

My invention is intended to provide a convenient and pleasing shape or configuration for cases for inclosing thermometers and pulsometers; and it consists of a case of a long narrow shape, uniformly square in perimeter and cross-section, and with rounded ends.

It also consists in other minor features, which form a subordinate part of the whole design, as will be fully hereinafter set forth.

In the accompanying drawings, serving to illustrate my design, *a* represents the lower portion or body of the case, and *a'* the top part or lid. The general shape of the case is long and narrow, as is common in this class of articles when designed for special purposes. The exterior conformation of the case is of a square or quadrangular shape, generally uniform in cross-section. At each end of the case, near its extremity, the angles *b b b b* are lost in a rounded bevel, *c*, and both ends of the case

are rounded off abruptly, as shown at *d*, Fig. 1. Where the cover or lid joins the body of the case the angles are similarly beveled, and above the bevels on the body portion the outer contour of the case is circular, or approximately so, thereby presenting the appearance of a band between the bevels, as seen at *e*. Except as above-stated, where the bevel breaks the sharpness of the angles, the case is of quadrangular shape its entire length.

I claim as my invention—

1. As a new and original shape or configuration of cases for thermometers and pulsometers, a case or receptacle of uniformly square perimeter and cross-section and rounded ends, substantially as shown and described.

2. The design for a thermometer and pulsometer case, the same consisting of a quadrangular-shaped case with beveled terminal angles and rounded ends, as herein shown and described.

3. The design for a case for inclosing thermometers and other articles, the same consisting of a case quadrangular in its general outer contour, and having its angles beveled inward where the lid and body join, forming an indented outline within the edges of the case, substantially as shown and described.

MYER DITTEHOFER.
